UNITED STATES PATENT OFFICE

HORACE W. BULLOCK, OF SPRINGFIELD, MASSACHUSETTS, ASSIGNOR TO
HIMSELF AND ORVIS W. BULLOCK, OF SAME PLACE.

DESIGN FOR WATCH-KEYS.

Specification forming part of Design No. **8,799**, dated November 23, 1875; application filed November 6, 1875.
[Term of Patent 7 years.]

To all whom it may concern:

Be it known that I, HORACE W. BULLOCK, of Springfield, Hampden county, Massachusetts, have invented a new Design for a Watch-Key, of which the following is a specification:

My design for a watch-key is fully represented in the accompanying drawing, to which reference is made.

The design consists of the alternate plain bands *a* and diamond-figured bands *b* on a cylindrical stem, *d*.

Having thus described my invention, I claim—

The design for a watch-key, consisting of the alternate plain bands *a* and diamond-figured bands *b* on a cylindrical stem, *d*, as described.
